Term of patent 14 years

Int. Cl. D21—02

U.S. Cl. D34—5 GS

FIG. 1 is a side elevation of a golf club shaft showing my new design;

FIG. 2 is an enlarged detail of that portion of the golf shaft indicated by the bracket in FIG. 1;

FIG. 3 is a still further enlarged transverse section taken along the line 3—3 of FIG. 2 to more clearly bring out the design; and

FIG. 4 is a similarly enlarged transverse section taken along the line 4—4 of FIG. 2 to more clearly bring out the design.

I claim:
The ornamental design for a golf club shaft or similar article, as shown.
